Primary Examiner — Brian N Vinson(74) *Attorney, Agent, or Firm* — Leanne Taveggia Farrell;
Westman, Champlin & Kelly, P.A.(57) **CLAIM**

The ornamental design for a display fixture, as shown and described.

DESCRIPTION

FIG. 1 is a top, front, and right side perspective view of a first embodiment of a display fixture showing our new design;
FIG. 2 is a front elevational view thereof;
FIG. 3 is a rear elevational view thereof;
FIG. 4 is a top plan view thereof;
FIG. 5 is a bottom plan view thereof;
FIG. 6 is a left side elevational view thereof;
FIG. 7 is a right side elevational view thereof;
FIG. 8 is a top, front, and right side perspective view of a second embodiment thereof;
FIG. 9 is a front elevational view thereof;
FIG. 10 is a rear elevational view thereof;
FIG. 11 is a top plan view thereof;
FIG. 12 is a bottom plan view thereof;
FIG. 13 is a left side elevational view thereof; and,
FIG. 14 is a right side elevational view thereof.
The broken-line disclosure in the views is for illustrative purposes only and forms no part of the claimed design.
